Primary Examiner — George D Kirschbaum*Assistant Examiner* — Natasha Vujcic(74) *Attorney, Agent, or Firm* — Marshall, Gerstein & Borun LLP(57) **CLAIM**

The ornamental design for a lighting fixture, as shown and described.

DESCRIPTION

FIG. 1 is a perspective view showing a new design for a lighting fixture;

FIG. 2 is a bottom view of the lighting fixture of FIG. 1;

FIG. 3 is a top view of the lighting fixture of FIG. 1;

FIG. 4 is a front view of the lighting fixture of FIG. 1;

FIG. 5 is a rear view of the lighting fixture of FIG. 1; and,

FIG. 6 is a left-side view of the lighting fixture of FIG. 1;

and, FIG. 7 is a right-side view of the lighting fixture of FIG. 1. The broken lines in the drawings illustrate portions of the lighting fixture which form no part of the claimed design.

1 Claim, 5 Drawing Sheets(56)
